COMPRESSOR UNLOADER

Raymond C. McAllister, Painted Post, N. Y., assignor to Ingersoll-Rand Company, Jersey City, N. J., a corporation of New Jersey

Application August 25, 1934, Serial No. 741,442

4 Claims. (Cl. 251—140)

This invention relates to compressors, but more particularly to a compressor unloader adapted to unseat a compressor valve.

One object of the invention is to prevent injury to the valve plate by the lifting device.

Another object is to assure against leakage of fluid from the compressor through the unloader.

Other objects will be in part obvious and in part pointed out hereinafter.

10 In the drawing accompanying this specification and in which similar reference numerals refer to similar parts,

Figure 1 is a longitudinal elevation, partly in section, of a compressor equipped with an unloader constructed in accordance with the practice of the invention, and

15 Figure 2 is an enlarged view, in sectional elevation, of the compressor unloader.

Referring more particularly to the drawing, 20 20 designates, in general, a compressor comprising a cylinder 21 and heads 22 and 23 which form closures for a piston chamber 24 in the cylinder.

The piston chamber 24 contains a piston 25, double acting in the present instance, for compressing fluid admitted into the ends of the piston chamber by apertures 26 opening into an inlet chamber 27 in the cylinder 21. The fluid compressed by the piston 25 is discharged through apertures 28 opening into a discharge chamber 29 whence such fluid may pass through a conduit 30 into a storage receiver 31. The apertures 28 are controlled by suitable discharge valves 32 and the admission of fluid into the piston chamber is controlled by inlet valves seated in each of the apertures 26 and designated, in general, by 33.

35 The inlet valves, which are inserted into the apertures 26 through apertures 34 in the outer wall of the inlet chamber 27, comprise the usual valve seat 35 and a stop plate 36 connected to the valve seat as by means of a threaded stem 37 and a nut 38. On the valve seat 35 and the stop plate 36 are seating surfaces 39 and 40, respectively, for a valve plate 41 which is adapted to reciprocate between the seats 39 and 40 for controlling a port or ports 42 in the valve seat 35. A spring 43 interposed between the valve plate 41 and the seat 40 urges the valve plate 41 in the direction of the seating surface 39.

40 A closure is provided for the aperture 34 in the form of a cover 44 having an aperture 45 and the inner portion 46 of which is threaded to receive a guide member 47. The inner end of the guide member 47 seats against an end wall 48 of a valve retainer 49 seated upon the valve seat 35 to hold the valve assembly fixedly in the cylinder

21. In the skirt portion 50 of the valve retainer extending from the end wall 48 to the valve seat are ports 51 to afford communication between the inlet chamber 27 and the interior of the valve retainer, and on the outer surface of the end wall 5 48 is a stem 52 which extends into a bore 53 in the guide member 47 for maintaining the valve retainer substantially coaxial with the aperture 34 and, therefore, with the aperture 26.

The valve retainer encases a valve lifting device 54 comprising a plate 55 and a stem 56 which extends slidably into a bore 57 in the end wall and the stem 52 of the valve retainer. The plate 55 carries fingers 58 which extend into the ports 42 of the valve seat to a point closely adjacent 15 the seating surface 39 and are of such length that they will be out of contact with the valve plate 41 in the retracted position of the lifting device.

The lifting device is normally held out of engagement with the valve plate 41 by a spring 59 interposed between the valve seat 35 and the plate 55.

In the form of the invention illustrated the lifting device 54 is adapted to be actuated manually. To this end an actuator 60, consisting of a rod, is disposed within the guide member 47 for actuating the lifting device 54 to lift the valve plate 41 from the seat 39. The outer end of the actuator 60 carries gripping portions 61 for rotating the actuator 60 and near the other end of the actuator 60 is a threaded portion 62 which engages threads 63 in the guide member 47. A collar 64 adjacent the threaded portion 62, and which may be an integral portion of the actuator 30 35 60, serves as a seat for a spring 65 acting against the stem 56 of the lifting device 54.

The spring 65 is of higher scale than the spring 59 so that when the actuator 60 is being manipulated to lift the valve plate 41 the movement 40 thereof will be positively transmitted through the spring 65 and the lifting device 54 to the valve plate.

Means are provided for definitely limiting the degree of movement of the actuator in order that complete compression of the spring 65 and, therefore, the establishment of a rigid path between the actuator 60 and the valve plate 41 may be avoided. The means serving this purpose are in the form of seating surfaces 66 and 67 on the 50 free end of the stem 52 and in the bottom of the bore 53, respectively, for the ends of the flange 64. The seating surfaces 66 and 67 are so spaced with respect to each other that the distance which the flange 64 may travel will be only of sufficient 55

extent to allow the spring 65 to be compressed to a degree that will assure lifting of the valve plate 41 from the seating surface 39 without, however, making it possible to fully compress the spring 59 and thus cause the fingers 58 to puncture or distort the valve plate.

In addition to the function described the flange 64 also serves to prevent leakage of fluid through the guide member 47 to the exterior of the compressor. The outer and inner ends of the flange 64 accordingly constitute sealing surfaces 68 and 69 which, in the limiting positions of the actuator 60, cooperate with the surfaces 67 and 66 to effect fluid tight joints. Thus, when the actuator 15 is shifted to a position for lifting the valve plate 41 the flange 64 bears against the surface 66 and prevents the passage of fluid through the guide member 47, and in the fully retracted position of the actuator the flange bears against the seating surface 67 and prevents such fluid as may enter the bore 53 from passing through the guide member to the atmosphere. The guide member 47 20 may, however, be additionally sealed on its periphery by a suitable packing device 70 in the cover 25 44 and by a packing device 71 disposed in its outer end to prevent leakage of fluid along the actuator 60.

During the normal operation of the compressor, the actuator 60 occupies a position in which the flange 64 seats against the seating surface 67 and cooperates therewith to prevent leakage of fluid 30 through the guide member 47. The springs 65 and 59 are then extended and the lifting device 54 occupies a position in which the ends of the fingers 58 are out of contact with the valve plate 41 which may reciprocate freely for controlling the flow of fluid through the aperture 26. Whenever it is desired to effect unloading of the compressor the actuator 60 is rotated to move in 40 the direction of the seating surface 66. This movement of the actuator compresses the springs 65 and 59 and advances the fingers 58 against the valve plate 41. Continued movement of the actuator 60 in the same direction causes the valve plate to be fully unseated and carries the flange 64 against the seat 66 to prevent leakage of fluid 45 from the inlet passage 27 into the bore 53.

I claim:

1. A compressor unloader, comprising a valve seat having a port, a valve plate for controlling the port, a valve lifting device for lifting the valve from the seat, an actuator for the lifting device,

guide members having seating surfaces thereon, a spring for transmitting the movement of the actuator to the lifting device, means on the actuator adapted to engage the seating surfaces for limiting the movement of the actuator, thereby preventing leakage of fluid through the guide members, and preventing the complete compression of the spring and the establishment of a rigid path between the actuator and the valve plate.

2. A compressor unloader, comprising a valve seat having a port, a valve plate for controlling the port, a valve lifting device for lifting the valve from the seat, an actuator for the lifting device, guide members having seating surfaces thereon, 15 a spring for transmitting the movement of the actuator to the lifting device, a lateral projection on the actuator adapted to engage the seating surfaces to prevent leakage of fluid through the guide members and to limit the movement of 20 the actuator, thereby preventing the complete compression of the spring and the establishment of a rigid path between the actuator and the valve plate.

3. A compressor unloader, comprising a valve seat having a port, a valve plate for controlling the port, a valve lifting device for lifting the valve from the seat, an actuator for the lifting device, guide members for the actuator and the lifting device having seating surfaces thereon, a spring 30 for transmitting the movement of the actuator to the lifting device, a flange on the actuator adapted to engage the seating surfaces to limit the movement of the actuator for preventing complete compression of the spring and to prevent 35 leakage of fluid through the guide members.

4. A compressor unloader, comprising a valve seat having a port, a valve plate for controlling the port, a valve lifting device for lifting the valve from the seat, an actuator for the lifting device, 40 guide members for the actuator and the lifting device having seating surfaces thereon, a spring for transmitting the movement of the actuator to the lifting device, a flange on the actuator adapted to engage the seating surfaces to limit 45 the movement of the actuator for preventing complete compression of the spring and to prevent leakage of fluid through the guide members, and a spring to normally hold the lifting device disengaged from the valve plate.

RAYMOND C. McALLISTER.
